UNITED STATES PATENT OFFICE

156,324

BATHTUB SEAT

Nathalie Dastugue, San Francisco, Calif.

Application September 20, 1948, Serial No. 148,668

Term of patent 14 years

(Cl. D15—8)

To all whom it may concern:

Be it known that I, Nathalie Dastugue, a citizen of the United States of America, residing at San Francisco, in the county of San Francisco and State of California, have invented a new, original, and ornamental Design for a Bathtub Seat, of which the following is a specification, reference being had to the accompanying drawing, forming a part thereof.

Fig. 1 is a perspective view of a bathtub seat showing my new design; and

Fig. 2 is a side elevational view of the same.

I claim:

The ornamental design for a bathtub seat, substantially as shown.

NATHALIE DASTUGUE.
